PHONOGRAPH

Frederick L. Fox, Washington, D. C., assignor to
 Thomas A. Edison, Incorporated, West Orange,
 N. J., a corporation of New Jersey

Application February 24, 1933, Serial No. 658,418

16 Claims. (Cl. 274—17)

This invention relates to commercial phonographs known as dictating and transcribing machines.

An object of the present invention is to provide practical means for preventing damage being done to the record or stylus of a phonograph by the improper removal from or application of the record to the machine, or by movement of the record on its support or mandrel while either 10 stylus engages the record.

Another object is to provide means whereby collapsing of the mandrel to allow movement of the record, will cause the stylus to be removed from the record.

Still another object is to prevent the improper removal or application of the record, by improved means which is considerably more simple in operation, cheaper to manufacture, and more positive in action than similar devices heretofore employed.

Other and more specific objects and features of the invention will become apparent from the following description when considered in connection with the accompanying drawings, in which:

25 Figure 1 is a fragmentary side elevational view of a commercial phonograph embodying the present invention.

Figure 2 is a view thereof partly in front elevation and partly broken away and in section.

30 Figure 3 is an enlarged fragmentary view of the mandrel and record, partly in elevation and partly in longitudinal section.

Figure 4 is an end elevation looking toward the left of Figure 3.

35 Figure 5 is a view similar to Figure 4 with the record stop or guard members contracted.

Figure 6 is a transverse section on line 6—6 of Figure 3.

40 Figure 7 is a transverse section on line 7—7 of Figure 3.

Figure 8 is a transverse section on line 8—8 of Figure 3.

Figure 9 is a detail section on line 9—9 of Figure 1.

45 Figure 10 is an enlarged perspective view of the cam forming part of the operative connection between the collapsible mandrel and guard members and the control for the recorder and reproducer.

50 Figure 11 is an enlarged fragmentary perspective view of one of the rods forming part of the collapsible mandrel shown in Figure 3.

Figure 12 is a transverse section on line 12—12 of Figure 3.

55 Figure 13 is a view similar to Figure 3 of a modified form of mandrel; and

Figure 14 is a view similar to Figure 13 of a still further modified form of mandrel.

60 Referring in detail to the drawings, 5 indicates the mandrel of the phonograph adapted to sup-

port the usual record R. The phonograph embodies a bed plate 6 provided with standards 7 and 8, and supported at one end in the standard 8 is a stationary tube or sleeve 9 secured rigidly in position by a set screw 10, or equivalent means. The driving shaft 11 for the mandrel 5 is mounted to extend through the tube 9 and has its inner or left hand end journaled within a suitable bearing in the corresponding end of the tube or sleeve 9. The shaft 11 is tubular or hollow and has its inner or left hand end extended between the standards 7 and 8 where it has a gear 12 secured thereon. From this gear 12, by connections not shown, the usual feed screw of the phonograph is driven in a well known manner to cause movement of the carriage 13 and the recorder and reproducer 14 supported thereby, relative to the record R on the mandrel 5. A collar 15, secured by a set screw 16 or the like to the outer or right hand end of shaft 11, engages the corresponding 10 end of the tube 9 and the enlarged inner end of shaft 11 engages the standard 8 to prevent the shaft 11 from shifting longitudinally with respect to the tube 9.

Power is transmitted to the driving shaft 11 by means of a belt 17 passing around a pulley 18 rotatable upon the stub shaft 19 secured in the standard 7 by a set screw 20 or the like. Any suitable means is employed to prevent movement of the pulley 18 axially of the shaft 19, 30 and said shaft 19 is in line with the shaft 11. The pulley 18 is adapted to be connected to shaft 11 by a clutch 21 which is slidable back and forth upon the enlarged inner end portion of shaft 11, and the movement of which is controlled in the usual manner by means including a shifting fork 22.

By way of example, the present invention is illustrated in connection with a phonograph having a collapsible mandrel of the general type disclosed in the U. S. patent to N. H. Holland, No. 1,213,197, January 23, 1917. This mandrel or record support comprises a tubular hub 23 rotatably mounted at its inner end upon the tube 9 and secured at its outer or right hand end by the set screw 16 onto the collar 15 which is secured by said set screw 16 to the adjacent projecting end of the driving shaft 11. Thus, the tubular hub 23 will rotate with or be driven by the shaft 11. A pair of disks 24 and 25 are mounted in adjacent relation on the tubular hub 23 adjacent the inner or left hand end thereof, the disk 25 being loose on this hub 23, and the disk 24 being secured thereto by a set screw 26 or the like. The disks 24 and 25 are resiliently connected by means of a spiral spring 27 arranged therebetween, and the disk 24 is provided with a number of similar and equally spaced slots 28. The disk 25 is provided with a corresponding number of slots 29 of the same size as the 50

slots 28, and the outer walls of all of the slots 28 and 29 are located at the same distance from the axis of the shaft 11, the slots 28 being arranged radially of the axis of the mandrel, 5 and the slots 29 in disk 25 being arranged at acute and equal angles to the slots 28, as clearly shown in Figure 6. The record support or mandrel further includes rods or members 30 extending longitudinally of the hub 23 and adapted to engage the bore of the cylindrical phonograph record R. These rods correspond in number to the number of slots 28 or 29, and the inner ends thereof are formed with slightly reduced cylindrical portions 31 seated in pairs of the cooperating slots 28 and 29 of disks 24 and 25. Spring 10 27 is so arranged that, whenever the reduced end portions 31 of rods 30 are seated in the cooperating pairs of slots 28 and 29, it will be under tension and constantly tend to turn or 15 rotate disk 25 on hub 23 with respect to disk 24, whereby the inner ends of rods 30 are normally maintained in the outermost position in engagement with the outer walls of the slots 28 and 29, as shown. The inner ends of the rods 20 30 are thus mounted to simultaneously and correspondingly yield toward the axis of the mandrel or record support as the record is pushed thereon, as clearly set forth and explained in the patent referred to above. However, the outer or 25 right hand ends of the rods 30 are mounted and actuated in a novel and special manner in accordance with the present invention, as will later 30 become apparent.

The carriage 13 for the recorder and reproducer 14 is slidably mounted on rods 32 and 33 to move parallel with the mandrel or record support 5, the carriage being fed along such rods to cause the recorder and reproducer to traverse the record cylinder mounted on said mandrel. 35 The recorder and reproducer 14 is set with respect to the record cylinder R on the mandrel, by suitable means comprising an arm or lever 34 having a splined connection with the rod 33 which is mounted to turn in bearings of the standard 7 and a further standard 35 on the right hand end of the bed plate 6. As usual, the arrangement of the lever 34 is such that when it is in a forward position the recorder and reproducer will be adjusted in recording or dictating 40 position with the recording stylus in engagement with the record R; that when said lever 34 is in the vertical position of Figure 1, the recorder and reproducer will be in neutral or inoperative position with its styli disengaged 45 from the record R; and that when the lever 34 is in a rearward position, the recorder and reproducer is in reproducing or listening position with the reproducing stylus in engagement with the record R. It will be noted that in setting 50 the lever 34 in either of these positions the guide rod 33 is rocked in its bearings. The general object of the present invention, in one of its embodiments, is to utilize the rocking movement of guide rod 33 for expanding and collapsing the 55 mandrel 5, or for projecting stop or guard members into the path of the record R and for retracting them out of the path of said record, or both, whereby the mandrel will be collapsed for easy removal of the record when the styli 60 of the recorder and reproducer are disengaged from the latter, and will be expanded to prevent easy removal of the record from the mandrel when either stylus is engaged therewith, or whereby movement of the record longitudinally of the 65 mandrel or removal of the record from or ap-

plication of the same to the mandrel is positively prevented when either stylus is in record-engaging position, or both. The invention also contemplates retraction of the guard or stop members to permit removal of the record when the recorder and reproducer is in neutral position with the styli disengaged from the record.

In carrying out the present invention, a longitudinally slideable rod 36 is arranged to extend through the shafts 11 and 19 with one end thereof projecting beyond the standard 7 and operatively connected with the rod 33, and with the other end thereof projecting beyond the right hand end of shaft 11 and operatively connected with 10 expansive and contractible record guard or stop members carried by the adjacent end of the mandrel, or operatively connected with the adjacent outer ends of the mandrel rods 33, or both.

As shown in Figures 1 to 12 inclusive, a plurality of arms 38 are arranged in equally spaced relation about and longitudinally of the hub 23 at the outer end of the latter, said arms being pivoted to the hub 23 at their inner ends as at 20 39 for swinging movement radially of the mandrel axis. The arms 38 are provided with cam slots 49 engaged by pins 41 arranged about and carried by a cap member 42 slideable upon the adjacent free outer end of the hub 23. The rod 36 is threaded through the end wall of cap member 42, and it will thus be seen that said cap member may be reciprocated by corresponding movement of 25 rod 36 so as to cause expansion or retraction of the arms 38, depending upon the direction in which the rod 36 is moved. A jamb nut 43 is threaded on the rod 36 against the outer side of 30 the end wall of cap member 42 to lock the rod 36 against adjustment or movement with respect to cap member 42 after having been properly adjusted relative to the same. Such proper adjustment of the rod 36 with respect to cap member 42 may be effected by loosening the jamb nut 43 and turning the rod 36 with respect to cap member 42 by engagement of a screw driver with a kerf in the outer or right hand end of said rod 36.

It will be noted that the guard or stop members 37, which are provided on the outer ends of arms 38, are arranged so that they will be in close proximity with the adjacent outer end of the cylinder R when projected, thus positively preventing any movement of said record longitudinally of the mandrel or record support, as well as positively preventing removal or application of a record with respect to the mandrel. In addition, the outer end portions of the arms 38 are arranged to flatly engage the bore of the outer end of record R, when said arms 38 and guard members 37 are expanded, as shown in Fig. 3, so as to form a rigid support and centering means for this end of the cylinder when the machine is in use. Also, the stop or guard members 37 are preferably of arcuate form and arranged concentric with the axis of the record support or mandrel so as to cooperate and present a nearly complete circular wall which will effectively prevent removal or application of the record, or over which the record cannot possibly be forced, and by means of which the record cannot possibly be marred to any material extent. At the same time, when the cap member 43 is moved to its outermost position as shown in Figure 2, the guard members 37 are sufficiently collapsed to easily pass through the bore of the cylinder and thereby permit easy removal or application of the record. In this form of the invention, the outer end portions of the rods 30 are operatively connected, 75

with the arms 38 by means of leaf springs 44 which straddle the arms 38 and are pivotally pinned to the latter adjacent the pivots of said arms 38 so that when the latter are expanded the adjacent outer ends of the rods 30 will be similarly expanded to grip the record and prevent its easy removal, as well as to sustain the record at its outer end until the arms 38 engage the bore thereof. Likewise, the connection of the rods 30 with the arms 38 will cause the rods 30 to collapse or move toward the axis of the record support at their outer ends when the arms 38 are retracted or collapsed, so as to permit easy application or removal of a record at that time.

The operative connection between the left hand end of rod 36 and the guide rod 33 is preferably as shown including a lever 45 pivoted intermediate its ends to the standard 7 as at 46 and having a fork at its lower end engaging in a circular groove of a collar 47 threaded on the adjacent end of rod 36, the upper end of lever 45 being reduced and operating in a double cam slot 48 provided in a horizontal flange of a cam member 49 secured to the adjacent end of guide rod 33. The connection at this point is such that when the guide rod 33 is rocked in one direction by operating lever 34 to set the recorder and reproducer in reproducing position, or when said rod 33 is rocked in the opposite direction by the lever 34 to set the recorder and reproducer in recording position, the rod 36 will be pulled to the left of Figure 2 to cause inward movement of cap member 42 and thereby expand the rods 30 of the mandrel and the arms 38 which carry the guard members 37. Movement of the record longitudinally of the mandrel or removal or application of the record with respect to the mandrel is thus positively prevented whenever the recorder and reproducer is set in either recording or reproducing position. In addition, the arrangement is such that when the lever 34 is moved to a vertical position as shown in Figures 1 and 2 to set the recorder and reproducer 14 in inoperative position with its styls disengaged from the record R, the rod 36 will be moved to the right of Figure 2 for correspondingly moving cap member 42 and collapsing the arms 38 and the outer ends of the mandrel rods 30. Thus, when the recorder and reproducer is set in neutral position, the guard members 37 are retracted and the mandrel is collapsed to permit easy application or removal of the record. The construction is of such character that movement of cap member 42 cannot be manually effected for collapsing or expanding the mandrel and the guard members, except by operation of the lever 34 which controls the setting of the recorder and reproducer with respect to the record. A suitable housing 50 is arranged about the arms 38 and adjacent parts to enclose and protect the same, said housing comprising a metal shell having longitudinal slots as at 51 to snugly accommodate the adjacent ends of rods 30 and permit their inward and outward movement, and attached to the cap member 42 as well as slidably fitting over the hub 23 of the mandrel. The cap member 42 preferably has a circular flange at its outer end provided with slots 52 to receive and guide the arms 38 in their swinging movement. Also, the collar 47 may be turned relative to the threaded end of the rod 36 to adjust the former, and the adjustment is retained by means of a jamb nut 53 threaded on said rod 36 against the collar 47.

In the modified form of construction shown in Figure 13, the arms 38a are connected by rigid

angular pieces 54 with the adjacent ends of the mandrel rods 30a, so that the adjacent outer end of the record will be rigidly centered and positively gripped when the arms 38a are expanded. In this form of the invention the arms 38a are terminated inwardly of the flange of cap member 42, the stop or guard members being omitted. Otherwise, this form of the invention corresponds to the construction described in connection with Figures 1 to 12 inclusive, the operation of cap member 42 being effected by connection of the rod 36 with the guide rod 33 of the phonograph.

Referring to the modification shown in Figure 14, the outer ends of the mandrel rods 30b are yieldingly connected by spring strips 44a directly with the hub 23 of the mandrel, no connection being provided between the rods 30b and the arms 38. Thus, in this embodiment, the mandrel is merely a yielding one and not expansible and collapsible by manual actuation. However, the arms 38 in this form of the invention carry the stop members 37 and are actuated by the rod 36, adapted for connection with the guide rod 33 as described and shown in connection with Figures 1 and 2. Also, in this embodiment, the arms 38 are adapted to rigidly center and support the record at its outer end when the arms 38 are expanded. Otherwise, the form shown in Figure 14 corresponds to the form of mandrel described and disclosed in connection with Figures 1 to 12 inclusive.

It will be noted that in the forms of the invention in which the rods of the mandrel are connected with the guard or stop carrying arms, the arrangement is such that the record is frictionally engaged by the mandrel when the mandrel is collapsed, with sufficient force to prevent accidental displacement of the record off of the mandrel, even though permitting its manual removal with relative ease. In other words, when the mandrel is collapsed, the record may be manually forced fully onto the mandrel into frictional engagement with the rods of the latter so as to retain the record in place under ordinary conditions. The expansion of the mandrel merely causes tighter frictional engagement of the mandrel rods with the record to prevent its easy removal. This is especially important in the form of the invention where the stop or guard members are omitted, but even where the latter are used, the arrangement serves the useful purpose of insuring retention of the record fully upon the mandrel under ordinary conditions even though the lever 34 be moved several times during the course of dictation to and from neutral position, with consequent repeated collapsing of the mandrel.

From the foregoing description, it will be seen that the present invention provides effective means for preventing the removal of a record from the machine, or its application to the machine when the recorder and reproducer is in either its recording or reproducing position, and that movement of the record on the mandrel is positively prevented until the recorder and reproducer is set in neutral position. It will also be understood that the invention is not limited to the specific constructions herein illustrated, it being apparent that the invention is not limited in many details, such as the use of an expansible or yieldable mandrel.

I claim:

1. In combination, a record support adapted to collapse to permit easy removal of a record, sound recording or reproducing means, means for

- controlling the engagement of the sound recording or reproducing means with the record, and means controlled by the last named means for expanding the record support when the sound recording or reproducing means is engaged with the record and for collapsing the record support when the sound recording or reproducing means is disengaged from the record.
2. In combination, a record supporting mandrel comprising a device operable to facilitate the removal of a record from the mandrel, sound-responsive means adapted to engage the record, means adapted to remove the sound-responsive means from record-engaging position, and means controlled by the last named means for operating said device when the sound-responsive means is removed from record-engaging position.
3. In combination, a rotatable record supporting mandrel having self-contained means actuatable to condition the mandrel so as to facilitate the removal of a record therefrom, sound-responsive record-engaging means, and manually operable means for simultaneously actuating the first-named means and moving the sound-responsive means to ineffective position.
4. In a machine of the character described, the combination of sound-responsive means, a mandrel expandable to prevent easy removal of a record therefrom, and means to expand said mandrel through movement of the sound-responsive means to record-engaging position.
5. In combination, a collapsible mandrel having an operating device actuatable to control the collapsing of the mandrel, sound-responsive means movable to and from operative position in respect to a record on said mandrel, a device for controlling the movement of the sound-responsive means, and means operated by said controlling device for actuating said operating device.
6. In combination, sound-responsive means movable to and from record-engaging position, manually operable means to move said sound-responsive means, a collapsible mandrel embodying a plurality of relatively movable rods, and means including movable members on the mandrel actuated by said manually operable means for retaining the record on said mandrel and expanding said rods when the sound-responsive means is moved to record-engaging position.
7. In combination, sound-responsive means movable to and from record-engaging position, a record-supporting mandrel comprising collapsible record-engaging members, and means including guard members on the mandrel to prevent application of a record thereto until the sound-responsive means is moved from record-engaging position and the record-engaging members are collapsed.
8. In combination, a mandrel, sound-responsive means and a control therefor, and means mounted on the mandrel and movable by said control to and from position wherein the same will prevent the removal of a record from and the application of a record to the mandrel.
9. In combination, a record-supporting mandrel, sound-responsive means, means for moving the sound-responsive means to and from the record and to and from recording and reproducing position, and means movably mounted on the mandrel and actuated by the last named means to prevent the application of a record to or the removal of a record from the mandrel when the sound responsive means is moved either to recording or reproducing position.
10. In combination, a record support, a record retaining device carried thereby and movable to and from operative position, sound-responsive means adapted to engage a record mounted on the record support, means for rendering said sound-responsive means inoperative, and means operated by the last named means for moving said record retaining device to inoperative position.
11. In combination, sound-responsive means movable to and from record-engaging position, manually operable means to move said sound-responsive means, a mandrel, and means including movable members on the mandrel actuated by said manually operable means for retaining the record on said mandrel when the sound-responsive means is moved to record-engaging position.
12. In a device of the character described, a mandrel, a movable guide rod, a carriage having styli and movable along said guide rod, controlling means for controlling the position of said styli relative to a record or blank and for moving said rod, a guard movably mounted on the mandrel, and means operatively associated with said rod and said guard, said means being actuable upon and by reason of the movement of said guide rod to move said guard to such a position as to prevent the removal or positioning of the record or blank with respect to the mandrel when either stylus is moved to operative position with respect to a record or blank on the mandrel.
13. In a phonograph, an expandable and contractible record support, sound-responsive means movable to and from engagement with a record on said support, and means operatively connecting said record support and sound-responsive means whereby movement of the latter to record-engaging position will be accompanied by the expansion of said support.
14. In a phonograph, an expandable and contractible record support, sound-responsive means movable to and from engagement with a record on said support, and means operatively connecting said support and sound-responsive means whereby the contraction of said support will be accompanied by record disengaging movement of the sound-responsive means.
15. In a phonograph, a record support, means mounted on said support for movement to and from a position for preventing longitudinal movement of a record on the support, sound-responsive means movable to and from engagement with a record on the support, and means connecting said movably mounted means and the sound-responsive means whereby movement of the latter to record-engaging position will be accompanied by movement of such movably mounted means to the said position thereof for preventing longitudinal movement of a record on the support.
16. In a phonograph, a record support, means mounted on said support for movement to and from position for preventing longitudinal movement of a record mounted on the support, sound-responsive means movable to and from engagement with a record on the support, and means connecting said movably mounted means and the sound-responsive means whereby record disengaging movement of the latter will be accompanied by movement of such movably mounted means from the said position thereof for preventing longitudinal movement of a record on the support.
